UNITED STATES PATENT OFFICE.

RALPH E. THOMPSON, OF BROOKLINE, MASSACHUSETTS.

INDICATING MECHANISM.

1,253,300.

Specification of Letters Patent.

Patented Jan. 15, 1918.

Application filed January 19, 1914. Serial No. 813,086.

To all whom it may concern:

Be it known that I, RALPH E. THOMPSON, a citizen of the United States, residing at Brookline, in the county of Norfolk and State of Massachusetts, have invented certain Improvements in Indicating Mechanisms, of which the following description, in connection with the accompanying drawings, is a specification, like reference characters on the drawings indicating like parts in the several figures.

In operating internal combustion engines it is important from the standpoint of economy to have the various adjustments of the engine so made that the engine will operate at its maximum efficiency. This is particularly true of the adjustments of the carburetor which controls the proportions of the fuel mixture. The average operator, however, is unable to determine, except very roughly, when these proportions are correct; and consequently he is unable to determine, except approximately, what changes in adjustments of the carburetors should be made to improve the operating efficiency of the engine. The most important factor to be determined is the relationship between the speed or travel of the engine and its fuel consumption, but in attempting to get at this relationship an operator is obliged to make such changes in adjustment as experience has indicated to be advisable and then to observe the resulting changes produced in the speed of the engine and in its fuel consumption. But these observations must be made over long periods of operation in order to obtain even approximately accurate results; and even under such circumstances other elements than those under consideration may so modify the conditions as to make the apparent results misleading.

It is the chief object of the present invention to devise an apparatus that will indicate the relationship between the travel of the engine and its fuel consumption; preferably giving the measure of one, in terms of the other.

An illustrative embodiment of the invention will now be described, reference being made to the accompanying drawings, in which:

Figure 1 is a front elevation of an indicator designed especially for use on automobiles;

Fig. 2 is a longitudinal, vertical, sectional view of the apparatus shown in Fig. 1;

Fig. 3 is a horizontal, sectional view on the line 3—3, Fig. 2;

Fig. 4 is an additional sectional view on the line 4—4, Fig. 2;

Fig. 5 is a side elevation, partly in section, of an additional part of the apparatus;

Fig. 6 is a diagrammatic view showing the electrical connections of the apparatus; and

Fig. 7 is a plan view showing the indicator applied to an automobile.

Briefly stated, the apparatus shown comprises an indicator, a mechanism operating in proportion to the fuel consumption of the engine, another mechanism operating in proportion to the speed of the engine, and means for so correlating the operations of these mechanisms that the indicator is caused to give the required information. The indicator may be calibrated to give its readings either in the number of strokes or revolutions that the engine makes on each gallon or other measured quantity of fuel; or the travel of the engine may be indicated in any other suitable manner. In an apparatus adapted especially for use on automobiles the indication may be given either in miles per gallon, or the fuel consumption may be indicated in terms of miles, as for instance in the pints required to cover a given distance, say ten miles. While these indications are equivalents, for most purposes the number of miles per gallon will be found the more convenient indication.

Referring now to the drawings, 2 indicates a casing having a face 4 held in position by a ring 6 screwed on to the casing 2, this face being provided with a window 8. A shaft 10 has its ends supported in the face 4 and the back wall 12 of the casing and mounted rotatably on this shaft is an indicating dial 14 carrying a series of figures which, as the dial turns, are brought successively in front of the window 8. The dial and apertured face 4 constitute the indicating elements of the apparatus. A spring 16, coiled about the shaft 10 and having one end fast thereto and its other end attached to the dial 14, tends to rotate the dial in a clockwise direction.

The operating mechanism for the dial comprises a worm gear 18 rotatably mounted on the shaft 10 just behind the dial 14 and a worm 20 which normally meshes with the gear 18 and is mounted in a small housing formed at one side of the casing 2. This worm is fast on a spindle 22 which is con-

ected through a swinging joint 24 with a flexible shaft 26 that may be driven either directly by the engine or indirectly by the machine which the engine drives. In the present instance this shaft is intended to be driven by suitable connections with a front wheel of an automobile and means may be provided to stop the rotation of the shaft when it is desired to stop the operation of the apparatus. The rotation of the worm 20 causes the worm gear 18 to turn on its axis in a counter-clockwise direction and this motion is transmitted to the dial 14 through a pair of metallic stops or contacts one of which, indicated at 28, is carried by the worm gear 18 while the other, indicated at 30, overlies the contact 28 and is carried by the dial 14. A spring 34, coiled about the shaft 10 and having one end fast thereto and the other end fast to the gear wheel 18, tends to rotate the wheel in a clockwise direction but the motion of the gear under the influence of the spring 34 is limited by a stationary stop 32 projecting inwardly from the casing 2. Since the spring 16 tends to turn the dial 14 in a clockwise direction and to maintain the contact 30 in engagement with the contact 28, it will be seen that the stop 32 determines the initial or zero position of both the dial and the gear wheel.

It will be evident that, as the worm 20 is rotated through the shaft 26 by suitable connections with the engine, the worm gear 18 will be turned on its axis and through the connections just described the dial 14 will be turned to bring the figures carried thereby successively past the window 8. The dial of course will be calibrated in accordance with the particular use for which the indicator is intended; but in the specific construction shown the calibration is given in miles. This part of the apparatus corresponds in general construction to an ordinary distance indicator or speed registering device.

The apparatus also comprises electromagnetic means controlled by a fluid measuring device in the fuel supply system for the engine by which the action of the operating mechanism for the indicator is interrupted when a given quantity of fuel has been consumed, and is started into operation again as the measuring device starts to measure another quantity of fuel.

In order to effect this interruption the worm 20 is mounted to swing on the pivot joint 24, as described above, and the upper end of the worm spindle 22 is mounted in a bushing 36 that is arranged to move in a guideway 38 formed in the housing for the worm. A spring 40, interposed between the bushing 36 and the wall of the housing, normally holds the worm in mesh with the worm gear 18. An electromagnet or solenoid 42 is secured to the back wall 12 of

the casing and the core 44 of this solenoid is connected by means of a small rod 46 mounted in suitable guides to the bushing 36 at the upper end of the worm spindle 22. It will be evident from an inspection of Fig. 4 that, when the solenoid is energized, the core 44 will be moved toward the right carrying the rod 46 with it, which will swing the spindle 22 far enough about the joint 24 to carry the worm 20 out of mesh with the worm gear 18. The rod 46 is provided with a small collar 48 which is arranged to be engaged by a gravity latch 50 pivoted on the wall 12 and serves to lock the rod temporarily against a return movement, which otherwise would take place as soon as the solenoid was again deenergized. This latch is tripped by a pin 51 carried by the gear 18 and arranged to engage the tail of the latch when the gear is in its initial position.

As soon as the worm 20 has been moved in the manner just described, the springs 16 and 34 tend to return the dial 14 and gear 18, respectively, to their initial positions. It is desirable, however, to retain each reading of the dial 14 for a substantial period of time after it has been moved to its indicating position. For this purpose the edge of this dial is toothed, as indicated in Fig. 2, and a small pawl 52, pivoted at 53, is mounted at one side of the casing in position to engage the teeth of the dial. A spring 54 normally holds the pawl in engagement with these teeth. Another solenoid 56, secured to the wall 12 of the casing, has a core 58 connected to one end of a small lever 60 fulcrumed on the casing at 62, Fig. 3 and engaging at its opposite end with the pawl 52. When this solenoid is energized, the movement of the core 58 is transmitted through the lever 60 to the pawl 52, swinging it out of engagement with the teeth of the dial 14 against the pressure of the spring 54, and consequently allowing the spring 16 to turn the dial backwardly until the contact 30 strikes the contact 28.

The measuring device may be of any form suited to the requirements of the particular engine with which the apparatus is used and it may either be operated by the flow of fuel to the engine, as in the case of rotary or displacement meters of well-known constructions, or it may be of a power operated type. The illustrative form shown is of the displacement type and comprises a casing or container 64 having a suitable inlet 65 connected with the tank or other source of supply, and an outlet 66 that is connected with the engine, an intermediate reservoir 67 preferably being included in the latter connection. It will be seen from an inspection of Fig. 5 that the outlet pipe 66 includes a siphon positioned in the middle of the casing 64 so that changes in the inclination of the casing will not appreciably affect the

siphoning action. The flow of liquid fuel into the measuring device is controlled by a valve 68 having a long stem vertically movable in suitable guides and projecting through the top of the casing where it has fixed thereto a core movable in an electromagnet or solenoid 69. This solenoid is provided with an upper and lower winding so that, when the upper winding is energized, 5 the core and the valve will be lifted, thus permitting the flow of fuel into the container 64; and when the lower winding is energized, the core will be moved into its lower position, thus seating the valve and 10 cutting off the further flow of liquid into the container. In order to hold the valve in either its open or closed position a small spring pressed detent 70 is mounted on the casing 64 in position to enter either one of 15 two notches formed in the valve stem, these notches being so spaced that the detent will retain the valve in either of its extreme positions.

Current for operating the solenoid 69 may 20 be obtained from any convenient source, indicated in the drawings as a battery A. One terminal of this battery is connected through a hand switch directly to the casing 64; while the opposite terminal is connected to 25 the common terminal of the two windings of the solenoid 69. The other terminal of the upper winding of this solenoid is connected to an insulated contact 71 mounted on the casing 64, while the other terminal of the 30 lower winding is connected to another insulated contact 72, also mounted on the casing.

The flow of current through these contacts and consequently through the windings 35 is controlled by a float 73 positioned within the casing, and arranged to slide on a vertical rod 74, the upper end of which extends through an aperture in the top of the casing, and the lower end being mounted for vertical movement in a socket formed in the bottom of the casing. Near its lower end, this rod has fixed thereto a collar 75 and a small spring presses upwardly against this collar and holds the rod in a raised position. 40 Above the container, the rod 74 has a horizontal arm carrying a contact 76 that is arranged to engage the contact 71 when the rod is lowered, this movement of the rod being effected by the float 73 striking the collar 75 when the container is nearly empty. Current may then flow from one side of the battery through the hand switch, the casing 64, rod 74, contacts 76 and 71, through the upper winding of the solenoid 69, and back 45 to the opposite terminal of the battery. The float 73 also carries an upright pin 77 that is adapted to project through an aperture in the top of the casing when the float is in its uppermost position, and to lift one end of a 50 pivoted switch arm 79, the opposite end of

which carries a contact arranged to engage the contact 72. When this engagement takes place, the current will then flow from the battery, through the hand switch, casing 64, switch arm 79, to the contact 72 and through the conductor leading therefrom to the lower winding of the solenoid, and thence to the opposite terminal of the battery. A small spring interposed between the switch arm 79 and the casing 64 opens 55 this switch as soon as it is released from the operation of the float 73 and its pin 77.

The horizontal arm of the rod 74 also carries a switch 78 which is insulated from this arm and is adapted to engage and connect 60 electrically two contacts 80, both mounted on the casing 64, but insulated therefrom. A conductor 82 is connected to one of these contacts and another conductor 84 is connected to the opposite contact, and these 65 conductors run to the indicating device, so that, when the rod 74 is depressed by the float, current can then flow through the switch 78 between the conductors 82 and 84.

It will now be understood that, when the 70 container 64 is empty, and the hand switch is closed, the weight of the float 73 on the collar 75 will bring the contacts 71 and 76 into engagement, thus completing the circuit through the upper winding of the solenoid 69 and lifting the valve 68 into its open position. The liquid fuel will then flow into the casing 64, lifting the float 73, thus breaking the engagement of the contacts 71 and 76, the detent 70, however, operating to maintain the valve open. It is 75 obvious that liquid cannot at this time flow out of the casing 64. As soon as the container 64 has filled, thus raising the float 73 to its uppermost position, the engagement 80 of the pin 77 with the switch 79 will close this switch, thus completing the circuit through the lower winding of the solenoid 69 and effecting the movement of the valve into its lowermost or closed position, where 85 it will be retained by the detent 70. When the container has filled, the liquid fuel will automatically start to siphon out of the discharge pipe 66, and this siphoning action 90 will continue until the level of the liquid has dropped far enough to admit air to the lower end of the pipe 66 within the casing 64. The cycle of operation above described 95 will then be repeated.

During the interval in which the container 100 64 is filling up, the engine will take its supply of fuel from the reservoir 67 into which the container empties, this reservoir having a capacity about equal to that of the container 64. A small air pipe 85 is connected 105 from the top of this reservoir to the air space in the container 64 above the maximum level of the liquid in the latter container. It will be noted that the reservoir 67 is positioned below the level of the top 110

of the container 64 so that, when both the reservoir and container are full, the liquid will stand in the air pipes 85 at the same level as the liquid in the container 64; but, 5 as soon as the engine begins to take fuel, the level in the container will drop while the reservoir remains full, and what liquid is used out of the reservoir while the container is filling up will be immediately replaced. 10 when the container begins to discharge again, so that the apparatus will measure with substantial accuracy the quantity of fuel used while the indicator is operating. It is obvious that the tank 64 will fill very 15 rapidly but that it may empty relatively slowly since its rate of emptying will be controlled by the rate at which the engine is taking fuel. The reservoir 67, of course, is practically always full. 20 The connections by which the measuring device 64 is enabled to exert its control over the indicator are shown diagrammatically in Fig. 6. From this diagram it will be seen that the conductor 82, leading from one 25 of the contacts 80 on the measuring device 64, is connected to a battery or other source of current B. The other conductor 84, leading from the other contact 80 on the measuring device, is connected to one of the stationary contacts of a switch 86, the other contact being connected by a conductor 88 to one terminal of the solenoid 56. The other terminal of the solenoid is connected by a conductor 90, in which a small hand 30 switch 92 is interposed, to the opposite side of the battery B. The switch 86 comprises the two contacts above mentioned and a movable contact carried by a pivoted switch arm 94 which is pivotally connected to the 35 core 44 of the solenoid 42. A spring 96 normally holds the switch 86 closed. The connections from the battery and measuring device to the solenoid 42 comprise the conductor 84, and a conductor 98 joined thereto 40 at the point 100 and running to one terminal of the solenoid 42. The opposite terminal of this solenoid is connected by a conductor 102 to the contact 28 carried by the gear wheel 18. Another conductor 104 connects the contact 30 on the dial 14 to the 45 conductor 90. It will be noted that the contacts 28 and 30 are insulated from their respective supports 18 and 14. The end of the conductor 98 opposite to its point of 50 connection with the solenoid 42 is connected to one of the stationary contacts of a switch 106, the other contact being connected by a conductor 108 to the conductor 82. The movable element of the switch 106 is carried by a pivoted arm 110, that is arranged to be moved to its closed position by the core 58 of the solenoid 56, a spring 112 normally holding the switch 106 open. 55

From these connections it will be evident 60 that the flow of current through the solenoid

56 is controlled by the measuring device 64 and by the solenoid 42 through its operation of the switch 86. Similarly, the flow of current through the solenoid 42 is controlled primarily by the measuring device 64 and 70 by the indicator and secondarily by the solenoid 56. The hand switch 92, of course, controls the entire operation of the electrical equipment.

The operation of the device is as follows: 75 Assuming the switch 92 to be closed and the parts to start from the positions in which they are shown in Fig. 2, the rotation of the worm 20 will turn the worm gear 18 and the dial 14 in the manner above described until 80 the contact 78 of the measuring device engages its coöperating contacts 80. The two contacts 28 and 30 at this time are in engagement and consequently current will flow through the switch 78, the conductors 84 85 and 98, the solenoid 42, conductor 102, contacts 28 and 30 and conductors 104 and 90 to the battery. Simultaneously current will flow through conductor 84, switch 86, conductor 88, solenoid 56 and conductor 90 to 90 the battery, so that both the solenoids 42 and 56 will be energized simultaneously. The energization of the solenoid 42, however, will immediately open the switch 86 before the switch 106 has had time to close, this result taking place by virtue of the relative ranges of movement of the switch arms 110 and 94 and by the relative tensions of the springs 112 and 96. Consequently, with this condition, the solenoid 56 is prevented from 95 tripping the pawl 52. The movement of the core 44 of the solenoid 42, however, causes the rod 46 to move the worm 20 out of engagement with the worm gear 18 and the latch 50 locks the parts in this condition. 100 The spring 34 immediately swings the worm gear backwardly to its initial or zero position, when the contact 28 strikes the stop 32 and the pin 51 strikes the tail of the latch 50, thus releasing the rod 46 and allowing 105 the spring 40 to move the worm 20 into mesh again with the worm gear 18. The dial 14 is retained in its previous position by the pawl 52 until it is again moved by the engagement of the contacts 30 and 28 or is released by the operation of the solenoid 56. 110

The worm 20, of course, immediately upon resuming its operative engagement with the worm gear 18 begins to turn the gear again in a counter-clockwise direction and continues this turning movement until its operation is again interrupted in the manner just described. Suppose now that the number 15 on the dial is opposite the window 8, indicating that the machine, during the interval 115 in which the last measured quantity of fuel was consumed, has traveled at the rate of 15 miles per gallon of fuel; and suppose that, at the time the contact 78 of the measuring device again engages its coöperating contacts 120

80, the machine has only traveled at the rate of 12 miles per gallon; or, in other words, the gear 18 has been moved to such a point that, if the contacts 28 and 30 were in engagement, the number 12 would be opposite the window 8. The current will then flow from the battery and through the switch 78, the conductor 84, switch 86, conductor 88, solenoid 56, and conductor 90 to the opposite pole of the battery thus energizing the solenoid 56 and causing the switch 106 to close. Current then can flow through the solenoid 56 by way of the conductors 82 and 108, switch 106, conductor 98, switch 86 and conductor 88 so that the solenoid 56 will continue to be energized even if the engagement of the contacts 78 and 80 is immediately broken. The current cannot at this time flow through the solenoid 42 for the reason that the contacts 28 and 30 are not in engagement. The movement of the core 58 of the solenoid 56, however, operates the lever 60 and trips the pawl 52, thus releasing the dial 14; whereupon the spring 16 immediately swings the dial in a clockwise direction until the contact 30 comes into engagement with the contact 28, thus moving the figure 12 opposite the window 8. Current then will flow from the battery either through the conductor 84, if the contacts 78 and 80 are still in engagement, or if this engagement has been broken, through the conductor 108, the switch 106 and conductor 98 to the junction point 100, and from there through the solenoid 42, conductor 102, contacts 28 and 30, and the conductors 104 and 90 to the opposite side of the battery. The energization of the solenoid 42 produced in this manner will immediately open the switch 86, thus deenergizing the solenoid 56 and releasing the pawl 52 which will be moved into engagement with the teeth of the dial 14 by means of the spring 54. At the same time, the rod 46 will swing the worm 20 out of mesh with the gear 18 and the latch 50 will catch the collar 48 on the rod 46 and serve to hold the worm 20 out of mesh with the worm gear 18 until the gear has returned again to its initial or zero position; when the latch will be tripped and the worm again will resume its operative position as above described. The pawl 52, of course, engages the dial 14 before the engagement of the worm 20 with the gear 18 is interrupted.

55 If, on the next measured quantity of fuel, the machine should travel at the rate of 17 miles per gallon, the worm gear 18 would move the dial 14 until the figure 17 came in front of the window 8, at which time the operation of the gear would be interrupted and the cycle of operations first described would be repeated.

It will be observed that the operation of the mechanism that moves the dial is stopped by the closing of the switch 78 and

is started again by the opening of said switch since the solenoid 42 will be energized and consequently will maintain the worm 20 out of mesh with the worm gear 18 until the switch 78 has moved out of engagement with the contacts 80. The design of the fuel measuring device preferably is such that its complete cycle of operations will be produced by the passage of a relatively small quantity of fuel, as for instance a pint, so that the readings will be given on the indicator at very frequent intervals when the machine is running at normal speed.

It should be noted that, even though the tank 64 may empty very slowly, due to the fact that the engine is taking fuel at a slow rate, the length of time during which the operation of the mechanism that drives the indicator is interrupted is very short. This operation is interrupted primarily by the engagement of the contact 78 with the contacts 80. At substantially the same time, however, that this engagement takes place, the contacts 71 and 76 are brought into engagement, thus causing the solenoid 69 to open the valve 68. The rush of liquid into the tank 64, which immediately follows, quickly raises the float 73 and breaks the engagement of the contacts 78 and 80, thus starting the driving mechanism for the registering means into operation again. The apparatus should be so designed that this interruption will be only long enough to effect the proper readjustment of the reading of the indicator. During this very brief interval of interruption, the engine takes so little fuel from the reservoir 67 that no substantial error is introduced by this action. Furthermore, this interval is nearly a constant so that allowance can be made for it. It will thus be clear that the operation of the registering means will be started substantially when the consumption of a given quantity of fuel is begun and will be stopped at substantially the instant that the consumption of this quantity of fuel is completed. This quantity, of course, is that emptied by the tank 64 in one cycle of operation of the apparatus.

It will now be understood that the apparatus shown comprises a distance-measuring means, a fuel-measuring means and electromagnetic connections and devices which enable the fuel-measurer to exercise a certain control over the distance-measurer and which correlate the results of the conjoint action of the two measuring means.

The apparatus enables an operator to determine very readily just what adjustments affecting the supply of fuel to the engine will give him the best results and enables him to make this determination quickly for different operating conditions. The apparatus also affords a check on the other ad-

justments of the engine since, if the operator finds that, with the usual adjustments of the carburetor and fuel controlling apparatus, the engine is not making its usual performance, it is evident that some factor other than these is responsible for the poor results obtained. I believe I am the first to devise an apparatus by which these advantages can be secured.

10 Fig. 7 indicates in a plan view and somewhat diagrammatically the manner in which the apparatus would be applied to an automobile, the indicator casing 2 preferably being secured to the dash-board and the container 64 connected at some convenient point in the gasoline line. The engine is indicated at 114 and the propeller shaft at 116. The flexible shaft 26 which drives the worm 20 is, in this arrangement, driven by a gear 20 connection 118 with the propeller shaft 116, this being a common connection for the operation of speedometers. Obviously, if desired the shaft 26 could be driven from one of the front wheels of the vehicle, this also 25 being a common method of driving a speedometer on a vehicle.

It will be understood that the term "travel" as used herein with reference to engines designate the total movement which 30 some moving part of the engine, as for instance the shaft, makes in a given time. For instance, this term as applied to a stationary engine would ordinarily designate the number of revolutions made by the engine shaft during the period in which the travel is being measured. As above stated, the indicating apparatus proposed by this 35 invention is of particular value in connection with the testing and operation of internal combustion engines, but it is obvious that the same apparatus might also be used with other types of engines or power plants which derive their power from fluid fuel and in which it is desirable to ascertain the 40 relationship between the fuel consumed by the engine or power developing unit and the mechanical movement produced by that engine or unit. The designation of the apparatus therefore as an apparatus for use with 45 internal combustion engines is intended not as a limitation, but rather by way of illustration of the more common use of the apparatus under present conditions. It will also be evident that while the apparatus 50 shown is arranged to give its indication in miles per gallon, it is within the spirit and scope of this invention to give its indication in gallons or fractions of gallons per mile or other given distance. In the arrangement described, the fuel measuring mechanism is standardized, that is, it measures a predetermined quantity of fuel at each operation while the distance measured varies; but it is clear that the mechanism for measuring the travel of the engine could be stand-

ardized while the fuel measurement was made a variable, if this arrangement were preferred for any reason.

It will be readily understood that the invention, considered in its broader aspects, 70 resides in a broad organization of elements rather than in the specific construction of those elements; and that the selection of elements made and the details of construction of the parts may be varied widely within 75 the skill of the mechanic and the discretion of the designer without departing from the spirit or scope of this invention. For instance, the fuel-measuring device may take many forms and may be of any one of several 80 different types, measuring either the entire quantity of fuel consumed or only a proportional part of the quantity consumed.

The fuel-measuring apparatus shown is of an old and well known type and while 85 any other suitable apparatus whether of the same or different type could be substituted for it, the apparatus shown embodies some specific features which will be made the subject matter of an additional application. 90

Having thus described the invention, what is claimed as new and desired to be secured by Letters Patent of the United States is:—

1. In an apparatus for use with internal combustion engines, an indicator, and operating means therefor comprising mechanism arranged to operate in proportion to the speed of the engine, additional mechanism arranged to operate in proportion to the rate of consumption of fuel by the engine, and means for correlating the operations of said mechanisms to cause said indicator to indicate directly the relationship between the travel of the engine and its fuel consumption. 100

2. In an apparatus for use with internal combustion engines, an indicator, and operating means therefor comprising mechanism arranged to be operated by the engine, additional mechanism operating in proportion to the rate of consumption of fuel by the engine, and means for correlating the operations of said mechanisms to cause said indicator to indicate the travel of the engine in proportion to its fuel consumption. 110

3. In an apparatus for use with internal combustion engines, an indicator having operating mechanism arranged to be driven by the engine, liquid measuring means arranged in the fuel supply system of the engine to 120 measure the consumption of fuel by the engine, and means controlled by said measuring means for causing said indicator to register at intervals, as each measured quantity of fuel is consumed, the total travel of 125 the engine on said measured quantity.

4. In an indicating apparatus for use with internal combustion engines, registering means arranged to be driven by the engine, and means controlled by the fuel supply for 130

the engine for causing said registering means to operate only during the consumption by the engine of a measured quantity of fuel.

5. In an apparatus for use with internal combustion engines, an indicator, operating means therefor comprising mechanism arranged to be driven by the engine, a measuring mechanism in the fuel supply system for the engine arranged to be operated by the flow of fuel to the engine, and means for correlating the operations of said mechanisms to cause said indicator to indicate the travel of the engine on a given quantity of fuel.

10. In an indicating apparatus for use with internal combustion engines, a registering means arranged to be driven by the engine, a fuel measuring mechanism arranged to operate in proportion to the rate of consumption of fuel by the engine, and means controlled by said mechanism for causing the operation of said registering means to start and stop, respectively, substantially when the consumption of a given quantity of fuel by the engine is begun and completed.

15. In an indicating apparatus for use with internal combustion engines, a registering means having operating mechanism arranged to be driven by the engine, additional mechanism arranged to operate in proportion to the rate of consumption of fuel by the engine, means controlled by said additional mechanism for causing the operation of said operating mechanism to start and stop, respectively, substantially when the consumption of a given quantity of fuel by the engine is begun and completed, and means for returning said operating mechanism to its initial or zero position after its operation has been stopped.

20. In an indicating apparatus for use with internal combustion engines, an indicating means having an operating mechanism arranged to be driven by the engine, additional mechanism arranged to operate in proportion to the rate of consumption of fuel by the engine, means controlled by said additional mechanism for causing said operating mechanism to start into operation when the consumption of a known quantity of fuel by the engine is begun and to interrupt said operation when the consumption of said quantity is completed, means for returning the operating mechanism of said indicator to its initial position after its operation has been interrupted, and means for retaining the reading of said indicator for a substantial period of time after said interruption.

25. In an apparatus for use with internal combustion engines, an indicator having operating mechanism arranged to be driven by the engine, liquid measuring means arranged in the fuel supply system of the en-

gine to measure the consumption of fuel by the engine, means controlled by said measuring means for causing said indicator to register at intervals, as each measured quantity of fuel is consumed, the total travel of 70 the engine on said measured quantity, and means for retaining each reading of said indicator during the greater part of the period in which the next measured quantity of fuel is being consumed.

30. In an indicating apparatus for use with internal combustion engines, a registering means having operating mechanism arranged to be driven by the engine, additional mechanism arranged to operate in 80 proportion to the rate of consumption of fuel by the engine, means controlled by said additional mechanism for causing the operation of said operating mechanism to start and stop, respectively, when the consumption of a given quantity of fuel is begun and completed, means for returning said operating mechanism to its initial position after its operation has been stopped, and means for preventing said operating mechanism from starting into operation again until said returning movement has been completed.

35. In an indicating apparatus for use with internal combustion engines, an indicating means having a movable indicating member and operating mechanism for moving said member, electromagnetic means arranged to interrupt the operation of said mechanism, means for returning said operating mechanism to its initial position upon such interruption, electromagnetic means operating normally to retain said indicating member in any indicating position but arranged to release said member, and controlling means for both of said electromagnetic means arranged to operate in proportion to the rate of consumption of fuel by the engine and to cause said indicator to register, as each given quantity of fuel is consumed, the 100 total travel of the engine on said quantity.

40. In an indicating apparatus for use with internal combustion engines, an indicating means having a movable indicating member and operating mechanism for moving said member, electromagnetic means arranged to interrupt the operation of said mechanism, means for returning said operating mechanism to its initial position upon such interruption, electromagnetic means operating 110 normally to retain said indicating member in any indicating position but arranged to release said member, a device arranged to operate in proportion to the rate of consumption of fuel by the engine, and connections between said device and both of said electromagnetic means for enabling said device to control the operation of said electromagnetic means, said connections being arranged to prevent the release of said indicat- 120

ing member while said operating mechanism is inoperative.

13. In an indicating apparatus for use with internal combustion engines, an indicator having a movable indicating member and operating mechanism for moving said member, electromagnetic means arranged to control the operation of said mechanism, electromagnetic means operating normally to retain said indicating member in any indicating position but arranged to release said member, and means for controlling the operations of both of said electromagnetic means including connections whereby the operation of one of said electromagnetic means is subject to the control of the other.

14. In an indicating apparatus for use with internal combustion engines, an indicator having a movable indicating member and operating mechanism for moving said member, electromagnetic means arranged to control the operation of said mechanism, electromagnetic means operating normally to retain said indicating member in any indicating position but adapted to release said member, a device arranged to operate in proportion to the rate of consumption of fuel by the engine, and connections whereby the operation of the second named electromagnetic means is controlled by said device and by said first named electromagnetic means, and the operation of the first named electromagnetic means is controlled primarily by said device and said indicator and secondarily by said second electromagnetic means.

15. In an indicating apparatus for use with internal combustion engines, the combination of mechanism comprising organized means arranged to operate conjointly in proportion to the speed of said engine and to the rate of consumption of fuel by said engine, and means to correlate the results of such conjoint operation.

16. The combination with an internal combustion engine and a fuel supply therefor, of an indicator, and operating mechanism for said indicator, said mechanism being connected with said fuel supply and said engine and being constructed and organized to cause the indicator to indicate directly the relationship between the travel of the engine and the rate of its fuel consumption.

17. The combination with a vehicle and a power plant using liquid fuel and arranged to drive said vehicle, of an indicating apparatus comprising distance registering means arranged to be operated by the vehicle, fuel measuring means operating in proportion to the rate of consumption of fuel by the engine, and means for correlating the operations of said means and giving the measure of one in terms of the other.

In testimony whereof I have signed my name to this specification in the presence of two subscribing witnesses.

RALPH E. THOMPSON.

Witnesses:

H. F. LYMAN,
GEORGE C. ORVEDSON.

Copies of this patent may be obtained for five cents each, by addressing the "Commissioner of Patents, Washington, D. C."

It is hereby certified that in Letters Patent No. 1,253,300, granted January 15, 1918, upon the application of Ralph E. Thompson, of Brookline, Massachusetts, for an improvement in "Indicating Mechanisms," an error appears in the printed specification requiring correction as follows: Page 6, line 110, claim 2, for the word "operating" read *arranged to be operated*; and that the said Letters Patent should be read with this correction therein that the same may conform to the record of the case in the Patent Office.

Signed and sealed this 26th day of February, A. D., 1918.

[SEAL.]

F. W. H. CLAY,

Acting Commissioner of Patents

Cl. 235—1.
